UNITED STATES PATENT OFFICE.

JOSEPH J. RING, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

ROTOR.

Application filed June 3, 1926. Serial No. 118,998

This invention relates in general to improvements in rotary structures, and relates more specifically to improvements in the construction and operation of rotors for various types of machines.

An object of the invention is to provide a new and useful rotor structure especially applicable to fluid actuated turbines, fluid pumps, conveyance propellers, or the like. Another object of the invention is to provide an adjustable vane rotor which is simple in construction and efficient in operation. A further object of the invention is to provide a rotor structure which is especially applicable to high speed rotary machines of various types. Still another object of the invention is to provide improved rotor vane adjusting mechanism which is compact in structure, and which may be readily manipulated either while the rotor is operating or when it is at rest. Another object of the invention is to provide a rotor and vane adjusting mechanism therefor, which may be manufactured at minimum cost and which can be conveniently assembled and dismantled. These and other objects and advantages will be apparent from the following description.

A clear conception of an embodiment of the invention and of the mode of adjusting the vanes of rotors constructed in accordance therewith, may be had by referring to the drawings accompanying and forming a part of this specification in which like reference characters designate the same or similar parts in the various views.

Fig. 1 is a part sectional general view of a hydraulic turbine installation embodying the improved rotor structure.

Fig. 2 is an enlarged fragmentary part sectional view of a portion of the rotor vane adjusting mechanism.

Fig. 3 is an enlarged sectional view of one of the improved rotors having adjustable vanes.

Fig. 4 is a fragmentary part sectional view through the improved rotor, the section being taken in the plane of the vane pivots.

Fig. 5 is an enlarged fragmentary part sectional view of the rotor, the section being taken through the hub cap of the improved rotor.

The hydraulic turbine installation to which the invention has been specifically applied

by way of illustration, comprises in general an axial turbine rotor 2 secured to the lower end of a main shaft 5 with the upper end of which an energy translating device 6 such as an electric generator, may be directly associated. The rotor 2 is housed within a main casing 7 the upper portion of which is provided with an annular series of adjustable inlet guide vanes 8 for directing water toward the rotor 2 through a vane-free transition space 10, and the lower portion of which forms a draft tube 11. The adjustable guide vanes 8 are manipulable by means of an actuating shaft 23 and are formed to receive their supply of fluid from an inlet flume 9. The draft tube 11 communicates with a tail-race 12 in the usual manner, and the entire turbine structure is supported upon a suitable foundation 13, as shown.

The rotor 2 comprises a hub 4 consisting of an outer shell portion and an inner central portion 41 formed integral with the outer shell portion and cooperating therewith to form a chamber 42; and a series of four dove-tail shaped non-overlapping vanes 3 having pivots 36 journaled in both the outer and inner hub portions. The rotor hub 4 is detachably secured to a lower flange 37 formed on the hollow main shaft 5, by means of cap screws 38, and the opposite end of the hub 4 is provided with a detachable cap 24 which encloses the chamber 42 surrounding the inner hub portion 41. The cap 24 is provided with a plurality of parallel guideways 28 formed to coact with rollers 39 mounted upon radiating pins 34 associated with an adjusting block 26. The adjusting block 26 is rigidly attached to the lower extremity of a vertically slid able adjusting shaft 25 by means of a clamping nut 27, and the shaft 25 extends upwardly through the central hub portion 41 and through the hollow main shaft 5. The portion of each vane pivot 36 which is located within the chamber 42, has a crank 30 secured thereto by means of a key 40, and the swinging ends of these cranks are connected with the radiating pins 34 of the block 26 by means of links 31 and pins 35. Each of the vane pivots 36 is moreover provided with an annular recess within which is located a thrust collar 32 which prevents outward displacement of the vane 3. The outer portion of each vane pivot 36 is journaled in an anti-friction or roller bear-

ing 29 carried by the outer hub portion, and the inner end of each vane pivot 36 is journaled in a socket 33 formed in the inner hub portion 41.

5 The upper extremity of the adjusting shaft 25 is provided with a collar 18 coacting through ball bearings with a casing 19. This arrangement permits the shaft 25 to rotate relatively to the casing 19, but enables 10 motion of the casing 19 longitudinally of the shaft 25 to be transmitted to the latter. The casing 19 is pivotally associated with the medial portion of a lever 14 one end of which is pivotally fulcrumed upon the end of a 15 swinging link 17, and the opposite end of which is pivotally connected to an adjusting block 20. The adjusting block 20 has screw thread coaction with an adjusting rod 21 the lower end of which carries the piston 22 of 20 a servo-motor 16, and the upper end of which is provided with an adjusting hand wheel 15.

During normal operation of the turbine unit disclosed in Fig. 1, the inlet guide 25 vanes 8 are adjusted to admit water to the turbine from the open flume 9. The water thus admitted is caused to advance through the transition space 10 and toward the rotor 2 in the form of a whirling mass or vortex. 30 As the whirling water strikes the pressure surfaces of the rotor vanes 3, it produces rotation of the main shaft 5 and of the rotor of the energy translating device 6, thereby converting a portion of the energy of the 35 water into useful work. The water after passing through the rotor 2 is delivered to the tail-race 12 through the draft tube 11 in a well known manner.

If it is desired to vary the angularity of 40 the vanes 3 relative to the rotor hub 4, such adjustment may be effected either manually by turning the hand wheel 15, or automatically by admitting fluid under pressure to one side of the piston 22 of the servo-motor 16 and by simultaneously releasing the 45 pressure upon the opposite side of the piston 22. Movement of the piston 22 or of the adjusting block 20 by manipulation of the hand wheel 15, causes the lever 14 to 50 swing about its fulcrum pivot at the upper end of the link 17, and causes the casing 19 to shift the adjusting shaft 25 vertically within the main shaft 5.

As the adjusting shaft 25 is slid within 55 the hollow main shaft 5 and the central portion 41 of the hub 4, the adjusting block 26 is simultaneously moved along the guideways 28 thereby shifting the adjusting links 31 and causing the cranks 30 to swing 60 the vanes 3 about the axes of their pivots 36. The rollers 39 coacting with the guideways 28 and with the pins 34, reduce to a minimum the friction resulting from the 65 sliding movement of the block 26, and the roller bearings 29 likewise reduce to a mini-

mum the friction resulting from turning of the vanes 3. The chamber 42 within the hub 4 as well as the interior of the cap 24 may be provided with grease or other lubricant in order to insure proper lubrication 70 of the bearing surfaces and to thereby further minimize the friction. The collars 32 coacting with the pivots 36 of the vanes 3, serve to prevent free escape of lubricant and also to prevent outward displacement 75 of the vanes without interfering with rotation thereof during adjustment.

In order to dismantle the rotor, it is merely necessary to remove the hub cap 24 whereupon the block 26 and the links 31 80 may be removed in an obvious manner. The thrust collars 32 are preferably formed as snap rings which are likewise accessible for removal upon removal of the cap 24. Upon removal of the thrust collars 32 the vanes 85 3 are free to be withdrawn endwise from within the cranks 30 and the bearings 29, 33.

From the foregoing description, it will 90 be apparent that the present invention provides a relatively simple and efficient adjustable vane rotor. The construction is especially applicable to high speed rotary machines such as hydraulic turbines, and the adjustment may be obviously effected 95 at any time. Due to its simplicity, the structure may be manufactured at minimum cost and the removable hub cap 24 insures convenient accessibility to all of the internal parts of the rotor.

100 It should be understood that it is not desired to limit the invention to the exact details of construction and operation herein shown and described, for various modifications within the scope of the claims may 105 occur to persons skilled in the art.

It is claimed and desired to secure by Letters Patent:

1. In combination, a hub having a chamber 110 therein, a cap normally enclosing said chamber, said cap having guideways therein, a plurality of vanes pivotally associated with said hub, a block movable within said cap, rollers for guiding said block along said guideways, and motion transmitting mechanism connecting said block and said vanes. 115

2. In combination, a hub comprising outer and inner portions separated by a chamber, a cap enclosing one end of said chamber and having guideways therein, a plurality of 120 vanes pivotally supported by said hub and having portions extending into said chamber, an adjusting shaft slidable within said hub, a block secured to said adjusting shaft, rollers for guiding said block along said 125 guideways, and linkage connecting said block with said vane portions within said chamber.

3. In combination, a main shaft, a hub 130 associated with said shaft, said hub com-

- prising an outer shell portion and an inner central portion, a plurality of vanes pivotally associated with both said outer and said inner hub portions, removable thrust collars 5 associated with grooves in said vanes and engageable with the inner surface of said outer hub portion to prevent outward displacement of said vanes, and means for adjusting said vanes about their pivotal axes.
- 10 4. In combination, a hollow main shaft, a hub associated with said shaft, said hub comprising an outer shell portion and an inner central portion, a plurality of vanes pivotally associated with both said outer and said inner hub portions, detachable means located in grooves in said vanes and cooperating with an inner surface of said outer hub portion for preventing outward displacement of said vanes, an auxiliary shaft 15 slidably disposed within said main shaft and said inner hub portion, a block rigidly attached to said auxiliary shaft adjacent to
- 20 said inner hub portion, said block being formed integral with said outer shell portion, and linkage connecting said block with each of said vanes between said outer and said inner hub portions.
5. In combination, a hollow main shaft, a hub associated with said shaft, said hub comprising an outer shell portion and an inner central portion, and said hub portions being formed integral, a plurality of vanes 25 pivotally associated with both said outer and said inner hub portions, an auxiliary shaft slidable within said main shaft and said inner hub portion, a block rigidly attached to said shaft adjacent to said inner hub portion, a cap coacting with said hub and enclosing said block, said block being slidable within and along surfaces of said cap, and linkage connecting said block with each of said vanes between said outer and said inner 30 hub portions.

In testimony whereof, the signature of the inventor is affixed hereto.

JOSEPH J. RING.
